UNITED STATES PATENT OFFICE.

JOHN D. RACE, OF EWING, NEBRASKA, ASSIGNOR TO FREDERICK R. BIGNOLD, OF EWING, NEBRASKA.

STAPLE-EXTRACTOR AND HAMMER.

SPECIFICATION forming part of Letters Patent No. 687,784, dated December 3, 1901.

Application filed April 13, 1901. Serial No. 55,732. (No model.)

To all whom it may concern:

Be it known that I, JOHN D. RACE, a citizen of the United States, residing at Ewing, in the county of Holt and State of Nebraska, 5 have invented certain new and useful Improvements in Staple-Extractors and Hammers; and I do hereby declare the following to be a full, clear, and exact description of the invention, such as will enable others skilled 10 in the art to which it appertains to make and use the same.

This invention has relation to tools embodying in their construction different parts for a variety of uses.

15 The present tool consists, essentially, of two parts pivotally connected, one part constituting the handle and the other being pivoted and movable relatively thereto.

For a full description of the invention and 20 the merits thereof and also to acquire a knowledge of the details of construction of the means for effecting the result reference is to be had to the following description and drawings hereto attached.

25 While the essential and characteristic features of the invention are necessarily susceptible of modification, still the preferred embodiment of the invention is illustrated in the accompanying drawings, in which—

30 Figure 1 is a side elevation of the tool. Fig. 2 is a perspective view. Fig. 3 is a detail perspective view of the pivoted member. Fig. 4 is a perspective view of the outer end portion of the handle. Fig. 5 is a transverse 35 section showing the interlocking connection between the hammer head and handle.

Corresponding and like parts are referred to in the following description and indicated in all the views of the drawings by the same 40 reference characters.

The tool comprises a handle 1 and pivoted member 2, the handle consisting of a bar flattened at one end and having its opposite end portion enlarged and made rounding to form 45 a grip 3, to the extremity of which is fitted a ring 4 by a swivel connection. The terminal of the flattened end portion is made rounding, and one side is roughened to form a file 5. The opposite side is cut away from one edge, 50 as shown at 6, to conform to the long arm or pointed end 7 of the pivoted member 2, so as

to receive said end and admit of its outer side and edge coming flush with respectively the side and edge of the handle 1. The pivoted member 2 is formed at its outer or pivotal end with a head 8, which projects beyond the inner side and lower edge of the member, the lateral extension overlapping the curved extremity of the handle and forming a close joint therewith, whereas the part projecting 60 from the lower edge is adapted to overlap the inner or lower edge of the handle 1 and limit the outward movement of the long arm or pivoted end 7 when the tool is used as a staple-extractor, punch, grapple or suspending 65 hook, and the like. This projecting portion also forms a hammer-head, the inner side of which inclines and is notched, as shown at 9, to form a claw for extracting nails and other headed fastenings. When the member 2 is 70 folded, as shown in Fig. 1, the tool can be used in the capacity of a hammer, nail-extractor, and claw, and when opened the part 7 is adapted for use as a staple-extractor, punch, reamer, hoof-cleaner, wire-stretcher, 75 hook, and the like. When used as a staple-extractor, the point 7 is driven through the closed end of the staple and the handle 1 is utilized as a lever for prying the staple from the part into which it has been driven. As a 80 wire-stretcher the end 7 can be engaged with the wire to be tightened in any desired manner, and by applying pressure to the handle 1 to turn the member 2 upon its end as a fulcrum the wire can be stretched to the required 85 degree. The wire or line may also be gripped between the head 8 and the lower edge portion of the handle, as will be readily understood.

A projection 10 is provided upon the lower 90 edge of the handle adjacent the pivotal connection of the member 2 therewith and is adapted to enter the notch 9 when the member 2 is opened and serves to brace the parts when subjected to lateral strain and relieve 95 the pivot-fastening between the parts 1 and 2 of a great amount of strain, thereby materially increasing the life and usefulness of the tool. This projection 10 also acts as a stop to prevent outward displacement of the wire or 100 line when gripped between the head 8 and the handle 1. It will thus be seen that the notch

9, in addition to forming a claw for extracting nails, also coöperates with the projection 10 to form positive interlocking means between the pivoted member and handle when 5 the part 2 is open.

Changes in the proportions, dimensions, and minor details of construction can be resorted to without in the least departing from the spirit of the invention.

10 Having thus described the invention, what is claimed as new is—

15 1. In combination, a handle having a portion of its side cutaway from one end and edge and having its extremity made rounding, and a member pivoted to the handle concentric with its curved extremity, said pivoted member having its long arm or end portion pointed and adapted to fit snugly within the cut-away portion of the handle and having a head at 20 its outer end overlapping the curved extremity of the handle and projecting beyond the inner edge thereof to form a hammer and adapted to engage with the inner edge of the handle and limit the opening of the pivoted 25 member, substantially as set forth.

2. A tool comprising a handle, a member pivoted to an end portion of the handle and having its outer or projecting end formed with a head constituting a hammer and a stop to

limit the opening of the pivoted member, and 30 interlocking means between the said head and handle to brace the parts when the pivoted member is open, substantially as set forth.

3. The herein-described tool comprising a 35 handle having a side portion cut away at one end and edge and having its extremity made rounding, a member pivoted to the handle concentric with the rounding end and having its long arm pointed and adapted to fit snugly 40 in the cut-away portion of the handle and having a head at its outer or projecting end to overlap the rounded end of the handle and to project beyond the inner or lower edge thereof, the projecting portion forming a hammer 45 and notched to provide a claw to overlap the inner edge of the handle and limit the opening of the pivoted member, and a projection at the inner edge of the handle to enter the notch of the claw, substantially as and 50 for the purpose set forth.

In testimony whereof I affix my signature in presence of two witnesses.

JOHN D. RACE. [L. S.]
